UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

SUPPORTING AND ADJUSTING MECHANISM FOR MINING-MACHINES.

1,267,675.

Specification of Letters Patent.

Patented May 28, 1918.

Original application filed September 30, 1911, Serial No. 652,099. Divided and this application filed March 7, 1913, Serial No. 752,742. Renewed October 16, 1917. Serial No. 196,975.

To all whom it may concern:

Be it known that I, NILS D. LEVIN, a citizen of the United States, residing at Columbus, in the county of Franklin and State of Ohio, have invented certain new and useful Improvements in Supporting and Adjusting Mechanism for Mining-Machines, of which the following is a specification, reference being had therein to the accompanying drawings.

This invention relates to improvements in coal cutting machines and more especially to mechanism for raising and lowering and adjusting the main operative parts of such machines with respect to the base.

The object of the invention is to provide an improved adjusting mechanism for mining machines by which the cutting mechanism and the parts associated therewith can be easily and quickly moved with respect to the base and secured in adjusted position.

This application constitutes a division of my co-pending application for mining machines, Serial No. 652,099, filed September 30, 1911.

In the accompanying drawings I have shown the embodiment of my invention which I now deem preferable.

Of the drawings,—

Figure 1 is a plan view of a mining machine embodying my invention;

Fig. 2 is a side elevation of the machine shown in Fig. 1, a second position of adjustment being indicated by dotted lines;

Fig. 3 is a fragmentary sectional view taken along the lines 3—3 of Figs. 2 and 4;

Fig. 4 is a fragmentary sectional view taken along the lines 4—4 of Figs. 1 and 3.

Fig. 5 is a fragmentary cross sectional view showing the means for retaining the turntable in place upon its support.

Figs. 6 and 7 are diagrammatic views showing one way in which the machine can be operated. In these views the machine may be considered as cutting either a room or an entry.

Figs. 8 and 9 are diagrammatic views showing another way in which the machine can be operated. In these views the machine is shown cutting according to the longwall method.

Referring to the drawings, 1 represents the frame and platform of the truck con-

stituting a rigid base upon which the other parts of the machine are mounted. The truck platform is supported on axles 2, 2^a, and track wheels 3, 3^a. One of the axles, as, for instance 2, is extended at one end and carries a sprocket wheel 4, the purpose of which will be more fully described hereinafter.

At three separated points on the truck platform 1 are secured upright guides 5, 6 and 7, two of these guides being arranged at the front corners of the truck platform, while the third is arranged centrally on the rear part of the platform. One of these guides is shown in vertical cross section in Fig. 3. 8 is an annular ring or frame to which brackets or bosses 9, 10 and 11 are secured. The brackets 9, 10 and 11 are provided respectively with guide lugs 12, 13 and 14 which are positioned to engage with the operative parts of the guides 5, 6 and 7. Each of the lugs 12, 13 and 14 is provided with a vertical aperture through which extends an adjusting screw 15. The lower end of each adjusting screw 15 is provided with a hardened bearing pin 16 which rests upon a hardened bearing plate 17 secured to the truck platform 1. The upper end of each of the screws extends through and has a bearing in a plate 18 secured to the top of the corresponding vertical guide bracket. The extreme upper end of each screw is adapted to be engaged by a wrench, the screws being shown square in the drawings. On each of the screws 15 there is a threaded nut 19 which engages with and supports one of the lugs 12, 13 or 14. Each nut is held against rotation by means of a pin 20 which projects into a suitable aperture formed in the nut. The supporting of the lower end of the screw on the smooth bearing plate 17 permits the lower end to move slightly horizontally to automatically accommodate itself to the movements of the nut as the frame is adjusted angularly. The bearing of the upper end of the screw in the plate 18 is sufficiently loose to permit this slight movement of the lower end.

It will be observed that by the construction which I have described, the ring 8 is rigidly held against horizontal movement, but at the same time may be readily adjusted vertically, either in horizontal parallel-

ism or angularly by simply turning the screws 15 by means of their squared upper ends.

21 represents a turntable which rests upon the ring 8 and upon which are mounted the operative parts of the machine. The turntable 21 rests directly upon the upper surface of the ring and is guided and held against horizontal movement by means of rollers 22, 22, which engage with the inner surface of the ring. In order to prevent the turntable from being lifted away from the ring, the table is provided with depending clips 23 which engage with the under surface of the ring.

The specific forms of construction of the cutting mechanism and the driving and controlling devices therefor form no part of my present invention and a detailed description of them will not be necessary. For such a description reference can be had to my co-pending application before referred to. It is sufficient here to point out that a horizontally-projecting elongated cutter frame 54 is provided which serves to support and guide a cutter chain 55, the frame 54 being rigidly secured to the turntable 21. The cutter chain is driven by means of a motor (not shown) which is mounted on the underside of the turntable and receives current through the cable 60. For rotating the turntable and the parts mounted upon it, there is provided a winding drum 49 which is driven, through suitable gearing, by the motor above referred to. A cable 51 is connected to the drum to be wound thereon. The end of this cable may be secured to one or another of the vertical studs or holders 52 which are provided on the ring 8. Horizontal idler sheaves 53 are arranged in a circumferential series on the turntable 21. Irrespective of which holder the end of the cable may be secured to, and irrespective of the position of the turntable, these sheaves 53 serve to guide the cable from the holder tangentially to the edge of the turntable. The cable can be used either to turn the table 21 and the cutting mechanism on the ring 8, or to advance the machine bodily along the track. When the machine is to be moved bodily as last mentioned, the turntable is locked against turning by means of a bolt 62 which can be raised to engage any one of a series of notches 63 formed in the edge of the turntable. By means of suitable mechanism, which is indicated generally by A, power can be transmitted (when the turntable is in one position) from the motor to the sprocket wheel 4 on one of the axles. By means of this power-transmitting mechanism, it is possible to drive the machine along the track by means of its own power.

Prior to my invention, it has been customary to cut kerfs in coal faces at or near the bottoms thereof. In many mines, how-

ever, conditions are encountered which make it preferable to cut the kerf at or near the top of the seam, or at some point between the top and the bottom. This is especially the case in mines where there are present in the coal seam bands or layers of impurities which must not be mixed with the coal. These layers are, of course, at different heights in different mines, and even vary markedly in height from place to place in the same mine. In fact, even in a given room the layer or band of dirt may be inclined so as to be much higher at one side than at the other. When such dirt bands are encountered, a machine embodying my invention can be used to cut them out; that is, the cutting mechanism is adjusted vertically, and angularly, if necessary, so that it will follow the dirt band and remove it, thus performing the double function of getting rid of the dirt and forming a kerf to permit shooting of the coal.

The operation of the raising and lowering mechanism will be understood from the foregoing description; but to make clear its utility in a machine such as herein set forth, reference is had to Figs. 6, 7, 8 and 9. These figures show two of the ways in which the machine can be operated.

Referring first to Figs. 6 and 7, it will be observed that the machine is here shown as operating on a track which extends along the center of a room to the face which is to be cut. From the mine entry the machine advances under its own power into the room and is brought to a position as close as is convenient to the face of the coal. The cutting mechanism is then extended toward the right, as shown in Fig. 6, and adjusted by means of the screws 15 to a suitable working height. Since each of the three adjusting screws can be operated independently of the others, the adjustment referred to can be such that the cutter arm will swing in horizontal planes or in planes inclined to the horizontal. The vertical adjustment of the cutter arm having been effected, the cable 51 is passed around the guide sheaves on the turntable and secured to one of the holders 52 as shown in Fig. 6. The cutting mechanism and the winding drum are then set in motion, the tension in the cable serving to swing the cutting mechanism from right to left to cause it to cut a semicircular kerf extending from one side of the room to the other. In Fig. 7 the kerf is shown half cut and the dotted lines indicate the position of the cutter after the completion of the cut.

After the cutting in one room is finished, the machine is moved by its own power over the tracks to another room where a more or less similar operation is repeated.

In Figs. 8 and 9 the machine is shown working on a track parallel to the coal face to be cut. The machine having advanced

130

under its own power to the point where the cut is to begin, the cutter arm is swung into the position indicated by dotted lines in Fig. 8. The cutting mechanism is then adjusted vertically to the proper working height, and, if desired, to a suitable inclination, by means of the screws 15. The cable 51 is then passed around the guide sheaves on the turntable and made fast to one of the holders 52. The cutting mechanism and winding drum are then thrown into operation and the tension of the cable serves to swing the cutter arm from the position shown in dotted lines to that shown in full lines in Fig. 8. When this full line position is reached, the feed is stopped and the cable is loosened, taken off from the holder 52 and extended along the face of the coal to a suitable jack 51^a as indicated in Fig. 9. The cutter arm is then locked against swinging by means of the bolt 62 and the winding drum is again started. The draft of the cable now serves to draw the entire machine along the track, the cutters meanwhile forming the kerf. In Fig. 9 the dotted line showing indicates the position of the machine at the beginning of this movement along the track, while the full line showing represents the machine after the cutting has progressed some distance. When the cut has been completed, the machine can be moved under its own power to another working place as will readily be understood.

In the present mechanism I have so arranged the upright supports that, as a system, they furnish a bracing support for the elongated cutting apparatus directly over the base structure, as in the case of earlier forms of construction designed by me; but it will be observed that in the present construction two of the supports are arranged to provide two relatively widely separated abutments close to the coal face, and preferably equi-distant therefrom, for receiving and resisting the reactions of the torsional stresses transmitted from the cutting apparatus as it swings across the front of the machine while at work, the rest of the system of supports being arranged in transverse vertical planes near the rear of the base structure.

What I claim is:

1. In a coal cutting machine, the combination of a rigid base, a frame above the base provided with three triangularly arranged outwardly extending vertically apertured lugs, three vertical screws extending through the said apertures respectively and rotatable independently of each other for adjusting the frame vertically or angularly with respect to the base, the said apertures in the lugs being relatively large and the said screws being normally out of engagement with the walls thereof, means on the base for supporting the screws, nuts engaging the

screws and connected with the frame, upright guides on the base arranged to engage with the lugs of the frame and prevent horizontal movement of the frame with respect to the base, and an elongated laterally movable cutting mechanism mounted on and extending horizontally from the said frame. 70

2. In a coal cutting machine, the combination of a rigid base, a frame above the base provided with a plurality of outwardly extending lugs, screws for adjusting the frame vertically with respect to the base, the said screws extending respectively through large apertures in the lugs, nuts on the screws below and in engagement with the lugs whereby the screws are normally out of engagement with the lugs, means for holding the upper ends of the screws against bodily movement, the lower ends of the said screws being freely movable horizontally under the control of the said nuts, means for preventing the rotation of the nuts, upright guides on the base arranged to engage with the lugs of the frame and prevent horizontal movement of the frame with respect to the base, and an elongated laterally movable cutting mechanism mounted on and extending horizontally from the said frame. 80

3. In a coal cutting machine, the combination of a rigid base, a normally horizontal circular frame above the base provided with three widely separated outwardly projecting lugs, three upright guides rigidly secured to the base and extending upward therefrom and each positioned and formed to engage one of the said lugs on three sides thereof to prevent movement thereof horizontally in any of three directions, means for adjusting the frame vertically with respect to the base, and an elongated laterally movable cutting mechanism mounted on and extending horizontally from the said frame. 95

4. In a coal cutting machine, the combination of a rigid base, a normally horizontal circular frame above the base provided with three widely separated outwardly projecting lugs, three upright guides rigidly secured to the base and each positioned and formed to engage one of the said lugs to prevent movement thereof horizontally in any of three directions, means for adjusting the frame vertically or angularly with respect to the base, and an elongated laterally movable cutting mechanism mounted on and extending horizontally from the said frame. 110

5. In a coal cutting machine, the combination of a rigid base, a normally horizontal circular frame above the base provided with three widely separated outwardly projecting lugs, three upright guides rigidly secured to the base and extending upward therefrom and each positioned and formed to engage one of the said lugs on three sides thereof to prevent movement thereof horizontally in any of three directions, mechanisms engag- 125

ing the said lugs respectively and operable independently of each other for adjusting the frame vertically or angularly with respect to the base, and an elongated laterally movable cutting mechanism mounted on and extending horizontally from the said frame.

6. In a coal cutting machine, the combination of a rigid base, an elongated laterally movable cutting mechanism extending horizontally from the base, and means carried by the base for operatively supporting and adjusting the cutting mechanism comprising a plurality of upright guides extending upward from the base frame and securely held in their upright positions at the angles of a horizontal polygon, said guides serving to prevent horizontal displacement of the cutting mechanism from its operative position, and means for supporting the cutting mechanism and adjusting it upward and downward in relation to the said guides.

7. In a coal cutting mechanism, the combination of a rigid base, three upright supports mounted on the base and extending upward therefrom, two of said supports being disposed at widely separated points near the front end of the base and the third support being located on the rear part of the base, a horizontally disposed frame vertically adjustably mounted on the three upright supports, and an elongated laterally movable cutting mechanism mounted on the horizontal frame and extending horizontally from the base in position to cut a horizontally extending kerf when moved laterally.

8. In a coal cutting mechanism, the combination of a wheel supported rigid base, a system of upright supports rigid with and extending upward from the said base and comprising two upright supports situated at widely separated points in a transverse vertical plane near the front end of the base to furnish two abutments close to the coal face and also a third upright support situated in a transverse vertical plane near the

rear end of the base, a horizontally disposed frame vertically adjustably mounted on all of the said upright supports, a laterally movable elongated cutter frame carried by the vertically adjustable frame and projecting forward from the base to intersect the transverse vertical plane of the said front supports, power driven endless chain cutter devices mounted to travel in a horizontal path around the periphery of the cutter frame, and means for moving the cutter frame when in operation laterally across the longitudinal vertical planes of the said front supports to form a horizontally extending kerf in front of the said base.

9. In a coal cutting mechanism, the combination of a wheel-supported rigid base adapted to run upon and be braced by the rails of a mine track, an elongated laterally movable endless chain cutter apparatus carried by the base and projecting horizontally therefrom, supporting means between the laterally movable cutter apparatus and the base comprising a plurality of upright supports extending upward from the base and held in upright positions at the angles of a relatively widely extended horizontal polygon, two of the said supports being situated at widely separated points near the front end of the base to furnish two abutments for the cutter apparatus close to the coal face, and connections between all of the upright supports and the cutter apparatus for sustaining said apparatus and adjusting it vertically in relation to the base, motor devices carried by the base, and driving connections whereby the power of said motor devices is caused to drive the cutter apparatus and to move it laterally, thereby forming a horizontally extending kerf.

In testimony whereof I affix my signature in the presence of two witnesses.

NILS D. LEVIN.
